UNITED STATES PATENT OFFICE.

FRANK McBRIEN, OF NEWARK, NEW JERSEY, ASSIGNOR TO THE UNION SWITCH & SIGNAL COMPANY, OF SWISSVALE, PENNSYLVANIA.

RAILWAY SIGNALING.

SPECIFICATION forming part of Letters Patent No. 681,030, dated August 20, 1901.

Application filed December 3, 1900. Serial No. 38,507. (No model.)

To all whom it may concern:

Be it known that I, FRANK McBRIEN, a citizen of the United States, residing at Newark, in the county of Essex and State of New Jersey, have invented or discovered certain new and useful Improvements in Electric Signaling, of which improvements the following is a specification.

The invention described herein relates to certain improvements in automatic signaling for railways.

It is customary in block-signaling, especially where the blocks are short, to employ home and distant signals, the home signal showing the condition of the block immediately following the signal and the distant signal showing the position of the home signal of the next succeeding block. As the distant signal is an indicator of the next succeeding home signal, it must be controlled thereby, and such control has been effected by means of a circuit-breaker on the home signal included in the circuit controlling the operation of the preceding distant signal. As long as this controlling-circuit was formed by conductors independent of the rails no trouble was encountered in the operation of the distant signal by the home signal; but since the introduction of the "wireless signaling system" for controlling electrically-operated signals, which involves the employment of polarized relays, trouble has been encountered, as the shifting of the circuit-changer by the movement of a home signal to clear its distant signal involves a rupture of the signal-circuit. The duration of this break in the signal-circuit of the block is exceedingly short, but is sufficient to release the electric slot of the preceding home signal, allowing that signal to go to "danger." It is true that this home signal, as well as the distant signal on the same post, will be immediately restored to "safety;" but the home signal might go to "danger" in the face of an approaching train, thereby necessitating a stoppage of the train, and the resetting of the home signal to "safety" involves a loss of power and unnecessary wear of the signal-operating mechanism.

The object of the present invention is to prevent a break in the signal-circuit during

the operation of the circuit-changer, thereby preventing the home signal from going to "danger" during such operation.

The invention is hereinafter more fully described and claimed.

In the accompanying drawings, forming a part of this specification, Figure 1 is a diagrammatic view illustrating the signals and circuit for two adjacent blocks and having my improvement applied thereto, and Fig. 2 illustrates a portion of the circuits at one station.

The operation of signals where the wireless circuit is employed is as follows: While the train is upon section A the signal H will be at "danger," as its operating or controlling circuit, consisting of battery 1, wires 2, 3, and 4, and armature 5 of relay 6, is broken by the deenergizing of the circuit of relay 6. The circuit of relay 6 consists of battery 7, wire 8, contact-point 9, non-polarized armature 10 of relay 11, and wire 12. The relay 11 is included in the track-circuit of section A and becomes deenergized by the entrance of a train on said section, so that its armature 11 will drop, breaking the battery-circuit through relay 6, thereby permitting armature 5 to drop and break the circuit of signal H. The circuit of distant signal D consists of battery 1, wires 13, 14, and 15, contact-point 16, and polarized armature 17 of relay 11, so that if the armature 17 is arranged to assume middle position when the relay 11 is deenergized the circuit of signal D may be broken by the entrance of a train into section A and the signal D go to "danger" with signal H. When the train passes off of section A onto section B, signal H' will go to "danger" through the deenergization of relays 11^a and 6^a, which have circuits similar to the circuits of relays 11 and 6, and the relay 11 of section A becomes energized to close through relay 6 the circuit of signal H; but in order to avoid the closure of the circuit in distant signal D, which is an indicator of signal H', the direction of the current through relay 11 is changed, so that the polarized armature of relay 11 will be held or drawn away from the contact-point 16, thereby causing or maintaining a break in the circuit of signal D. The change of direction of current through the rails of

the several track-sections is controlled by the home signal of each section or its operating or controlling mechanism—as, for example, by armatures of relays 6 6^a, &c. The track-circuit controlled by the armature includes both front and back contact-points 18 and 19, which are so connected with track-battery 20 that the track-circuit will be closed in both positions of the armature; but the direction of flow of current will be different. When the train passes off of section B, the armatures 11^a and 6^a will be again energized, thereby closing the circuit of signal H' and sending the latter to clear position. The movement of the signal H' to "clear" shifts the circuit-changer of the track-circuit of section A so that the direction of flow of current through such circuit and the relay 11 is reversed, thereby so shifting the polarized armature of said relay as to close the circuit on distant signal D, thereby clearing said signal.

It will be observed that the movement of the circuit-changer when the relay 6^a is energized will break momentarily the circuit of relay 11, so that its armature 10 will drop, thereby breaking the circuit of relay 6 and permitting the home signal H to go to "danger." It is true that this break is short, and the home signal will be immediately restored to clear position on the completion of the movement of the circuit-changer; but it involves an unnecessary movement of the signal; and, further, if a train should be approaching signal H its movement to "danger" will require a stopping or slowing up of the train.

In order to prevent a break in the circuit of the home signals when the circuit-changer operates as a train leaves a section, suitable means are provided for maintaining the circuits of the home signal during the operation of the circuit-changer. A convenient means to this end consists in so retarding the discharge or deenergizing of the relays 6 6^a, &c., that the armatures of the relays will be held against their front contacts during the operation of the circuit-changer. In other words, the relays 6 6^a, &c., are so constructed as to be operative to hold the circuits of home signals closed while their own circuits are broken and reestablished.

In the construction shown the circuit of the relay 6 or 6^a, &c., consists, starting from the battery 7, of relay 6, wire 12, armature 10 of relay 11, front contact-point 9, and wire 8 to battery. The armature 10 is so constructed that it will make contact with the back contact 21 before connection with contact-point 9 is broken. This operation may be effected by contact-springs 22, secured on opposite sides of the armature. These springs are so arranged relative to the distance between the front and back contacts 9 and 21 that as the

armature moves one of the springs will bear against its contact-point before the other 65 spring leaves its contact-point. The contact-point 21 is connected by a wire 23 with the relay 6 at a point between the battery 7 and the relay, so that when the armature 10 drops, due to the deenergizing of relay 11, a circuit 70 for the relay 6 without battery will be closed before its battery-circuit is broken. This closed circuit consists, starting from one pole of relay 6, of wire 12, armature 10, back contact 21, and wire 23 to the opposite pole of the 75 relay, as clearly shown in Fig. 2.

As is well known, the closing of the circuit of a charged relay when its battery-circuit is broken will retard the magnetic discharge of the relay. By properly constructing the relays 6 6^a, &c., in accordance with rules known in the art the discharge of relay 6 can be delayed or retarded sufficiently to permit of the operation of the circuit-changer and the recharging of the relay before the previous 85 magnetic charge is reduced sufficiently to release the armatures of the relays 6 6^a, &c.

The relays 11 11^a, &c., are shown as operating polarized and non-polarized armatures; but it will be understood by those skilled in the art that two relays—one with a polarized armature and the other with a non-polarized armature—may be used in lieu of the single relay with two armatures.

I claim herein as my invention—

1. In a railway signaling system, the combination of a series of insulated track-sections, home and distant signals for each section, relays having polarized and neutral armatures included in the track-circuits and controlling the signals, a relay controlling the home signals and controlled by the neutral relay in the track-circuit, and a circuit-changer at each section controlled by the home signal and controlling the track-circuit of the preceding section, substantially as set forth.

2. In a railway signaling system, the combination of a series of insulated track-sections, home and distant signals for each section, relays included in the track-circuits, the polarized relay controlling the distant signals, relays controlling the home signals, circuits without batteries and a normally-opened circuit including said relays, and normally-closed branches shunting the batteries of said circuits and controlled by the neutral relays included in the track-circuits, and circuit-changers controlling the circuits of preceding track-circuits and controlled by the home signals, substantially as set forth.

In testimony whereof I have hereunto set my hand.

FRANK MCBRIEN.
